UNITED STATES PATENT OFFICE

2,610,667

HYDRAULIC CORRUGATING MACHINE

Louis M. Puster, Knoxville, Tenn., assignor to
 Robertshaw-Fulton Controls Company, a corporation of Delaware

Application July 2, 1947, Serial No. 758,664

14 Claims. (Cl. 153—73)

1

This invention relates to hydraulic presses and more particularly to hydraulic presses for forming expansible and contractible corrugated metallic walls.

Heretofore various devices have been proposed for forming expansible and contractible corrugated metallic walls by spacing forming plates along a metallic tube at regular intervals, thereafter expanding the tube by internal hydraulic pressure until bulges form in the tube between plates, and thereafter forcing the forming plates toward each other to form corrugations in the tube between plates. Among such previous devices is that of the United States Patent No. 2,217,799, granted to Jean V. Giesler on October 15, 1940. In these devices many of the steps in the process of forming the expansible and contractible walls have been performed manually, slowing the production rate, and have introduced certain difficulties arising from the human factor of the operators.

The present invention obviates these prior difficulties, in a device that continues to use the broad idea of forming expansible and contractible metallic walls by spacing equidistantly a plurality of forming plates along a metallic tube, expanding the tube by hydraulic pressure forming bulges in the tube between the forming plates and thereafter forcing the forming plates together to form the desired corrugations in the tube, by providing automatic operation in the sequence of its functions thus producing a uniform product at greatly increased rates. In the present invention the operator places the metallic tube to be formed into the expansible and contractible wall on an arbor which is then automatically moved within the forming plates. When the tube reaches its final position within the forming plates the open end or ends of the tube are automatically closed. The forming plates are then automatically locked about the tube. When the forming plates are locked together hydraulic pressure is automatically exerted within the tube to form bulges in the tube between the forming plates. When the hydraulic pressure reaches a predetermined value it is thereafter automatically maintained at this pressure and at the same time suitable means are automatically energized which, at the start of their cycle, remove the spacers from between the forming plates. After removal of these spacers these means continue their cycle automatically to effect the formation of the desired corrugations in the tube between the plates as the latter move toward each other. When the plates reach a predetermined relation-

2

ship the hydraulic pressure within the now formed corrugated wall is automatically released, the forming plates unlocked and opened, the compressing force is automatically terminated and reversed and the arbor, with the now formed corrugated wall upon it, returned to its original position outside of the forming plates. The formed wall is then removed from the arbor. With the return of the forming plates to their original position mechanical means automatically return the spacers between the several forming plates. Another tube is then placed on the arbor in readiness for another forming cycle.

It is an object of this invention to provide a novel hydraulic press in which the several steps of forming the expansible and contractible wall are automatically performed at the proper time.

Another object of this invention is to provide a novel hydraulic press in which novel means are automatically actuated when the tube is in final position within the forming plates to automatically seal the open end or ends of the tube.

Another object of this invention is to provide a novel hydraulic press in which novel means are automatically actuated to introduce hydraulic pressure within the tube before the end or ends of the tube are sealed and to thereafter seal the end or ends of the tube.

Another object of this invention is to provide a novel hydraulic press in which novel means are actuated after the end or ends of the tube have been sealed but before the generation of bulging pressure to close and lock the forming plates about the tube.

Another object of this invention is to provide a novel hydraulic press in which novel means are automatically put into rectilinear movement when the hydraulic pressure within the tube has reached a predetermined value the initial movement of which acts to remove the spacers from between the forming plates.

Another object of this invention is to provide a novel hydraulic press in which novel means are automatically actuated when the forming plates have moved toward each other a predetermined amount to release the hydraulic pressure acting on the wall.

Another object of this invention is to provide a novel hydraulic press in which novel means are provided for automatically unlocking and opening the forming plates when the hydraulic pressure within the formed wall is released.

Another object of this invention is to provide a novel hydraulic press in which novel means are provided for automatically returning the end

sealing means with the formed wall upon it to its initial position outside of the forming plates as soon as the forming plates have been unlocked and opened.

Another object of this invention is to provide a novel hydraulic press in which novel means are provided for mechanically interposing the spacers between the forming plates at the proper time in the cycle of operation of the press.

Another object of this invention is to provide a novel hydraulic press in which novel means are provided for mounting the forming plates for automatically closing and locking and for unlocking and opening, all at proper times in the cycle of operation of the press.

Another object of this invention is to provide a novel hydraulic press in which novel means are provided for adjusting the relative position of the spacers.

Another object of this invention is to provide a novel hydraulic press which can be reversed at any time in its cycle of operation to return the several elements thereof to their initial positions in proper sequence without damage to the machine.

Other and further objects of this invention will appear as the description thereof proceeds.

With these objects in view an illustrative embodiment of the novel hydraulic press of the present invention is shown in the accompanying drawings but it is to be expressly understood that this embodiment is shown and will hereafter be described for the purpose of illustration only and should not be construed as a limitation of the present invention. Reference should be had to the appended claims to determine the scope of the present invention.

In the accompanying figures,

Figs. 1 and 1a are together a front view of one embodiment of my novel hydraulic press;

Figs. 2 and 2a are together a top view of the embodiment of my novel hydraulic press shown in Figs. 1 and 1a;

Fig. 3 is an enlarged view of a portion of Fig. 1 showing a typical forming plate in locked position, a novel plate locking means, the novel spacer removing means, the novel means for closing and locking and unlocking and opening the plates and the novel mechanical means for interposing the spacers between the plates;

Fig. 4 is a similar view to Fig. 3 showing the forming plates in unlocked and open position and the novel mechanical means for interposing the spacers between the plates in engagement with certain of the spacers;

Fig. 5 is an enlarged perspective view of a portion of Fig. 1 showing the novel cradle for supporting the forming plates, spacers and separators;

Fig. 6 is a perspective and enlarged view of a portion of Fig. 1 partly in section showing the novel means for removing the spacers from between the forming plates.

Fig. 7 is an enlarged sectional view of a portion of Fig. 1 through the forming plates showing in more detail the novel means for supporting the spacers and forming plates in the cradle and the position of the novel spacer removing means.

Fig. 8 is an enlarged sectional view of a portion of Fig. 1a showing in more detail the novel tube supporting and end sealing means;

Fig. 9 is a simplified piping diagram of the hydraulic system shown in Figs. 1 and 1a;

Fig. 10 is an enlarged view of a spacer separator;

Fig. 11 is an enlarged view of a spacer; and

Fig. 12 is a simplified partial piping diagram of a suitable modified hydraulic system for use with this invention.

In the several figures, in which like reference characters indicate similar parts, and more particularly with reference to Figs. 1-8, 11 is any suitable machine bed slotted at 12 for mounting the several parts of the device and supported by suitable legs 13. Mounted at one end of bed 11 are brackets 14 and 15 between which is carried a spacer reset piston and cylinder 16, and a closing or ram piston and cylinder 17, bolts 18 acting to hold the assembly together. Fluid under pressure is admitted to one side of the piston in cylinder 16 through hand-adjustable valve 19 and to the other side of the piston through hand-adjustable valve 20. Fluid under pressure is admitted to one side of the piston in cylinder 17 through hand-adjustable valve 249 and to the other side of the piston through pipe 251. The hydraulic system for operating these pistons in timed sequence in the cycle of operation of the machine will be described hereinafter in detail.

Mounted on bed 11 beyond bracket 15 are cradle brackets 23 and 24. Bracket 24 carries upstanding elements 25 and 26 which in turn carry parallel rods 27 and 28 which are secured at their other ends to bracket 15 as at 29 and 30. Mounted for reciprocating movement on said rods 27 and 28 is spacer reset head 31 which is operated by the piston in cylinder 16 through piston rod 32 that is secured to head 31 by manually operable lock 33. As seen in Figs. 3 and 4 spacer reset head 31 is provided with outwardly and downwardly extending parts 34 and 35 to which housings 38 are suitably secured as by bolts 36 and keys 37. Reset rollers 39 and 40 are rotatably mounted in housings 38. Rollers 39 and 40 are offset at their centers of rotation for reasons that will more fully appear hereafter.

Referring now more particularly to Figs. 3, 4 and 5, brackets 23 and 24 support a rod 41 extending parallel to the center line of bed 11. Pivotally mounted on rod 41 are cradle end elements 42, 43, 44 and 45. Elements 42 and 43 are pivotally mounted at 46 and together form one end of the cradle while elements 44 and 45 are pivotally mounted at 47 and together form the other end of the cradle. Elements 42 and 43 are kept in spaced relationship with elements 44 and 45 by spacer guide bars 48 and 49 on the one side and by spacer guide bars 50 and 51 on the other side. These guide bars are fixed to the cradle end elements in parallel relationship. Each guide bar is longitudinally slotted as at 52 and 53 for bars 48 and 50 and at 54 and 55 for bars 49 and 51 respectively to carry spacer locks 56 and 57. Mounted for reciprocating movement between the guide bars are a plurality of spacers 58 separated by separators 59 and limited in outward movement by stop members 60 and 61 carried by the cradle end elements.

As seen in Figs. 7, 10 and 11 the spacers 58 are of generally rectangular shape slotted at 62 and beveled at 63 for insertion between the forming plates as will more fully appear hereafter.

Spacers 58 are also beveled at 64 for engagement by the reset rollers 39 and 40. The separators 59 are more or less $\frac{1}{4}$ -shaped in plan and have slots 65 corresponding to slots 62 of spacers 58. Separators 59 have ears 66 and 67 formed integrally therewith and when in place between the guide

bars these ears are received by the slots 52—54 and 53—55. The thickness of separators 59 is determined by the thickness of the forming plates. A separator 59 is placed between each two adjacent spacers 58 and the number of such spacers and separators used in any setup of the machine is determined by the number of forming plates used which in turn is determined by the number of corrugations desired in the wall to be formed.

Spacer locks 56 and 57 hold spacers 58 and separators 59 together between the guide bars. As seen in Fig. 7 lock 56, which is duplicated by lock 57, comprises a body portion 68 mounted between the guide bars and locked in place by bolts 69 extending through slot 52 and cooperating with plate 70. Body portion 68 is drilled at 71 to receive springs 72 and bearing balls 73 which are resiliently urged against the adjacent separator 59 to pack the spacers and separators together and yet allow reciprocating movements by the spacers.

Spacers 58 are withdrawn from between the forming plates by square bars 74 and 75 moving in the slots 62 of the spacers 58 and in the slots 65 of separators 59. The ends of bars 74 and 75 are rounded (Fig. 6) and are received in rounded slots 76—79 in rocker arms 80—83 respectively. Arms 80 and 81 are secured to a rocker shaft 84 journaled in cradle end elements 42 and 44 and arms 82 and 83 are secured to a rocker shaft 85 journaled in cradle end elements 43 and 45. The rocker arms are located on the outside of the cradle end elements and the cradle end elements are suitably cut away to allow movement of bars 74 and 75. Arms 80 and 82 are rocked by cam followers 86 and 87, respectively, which are pivotally mounted at 88 and 89 on bracket 15. Cam follower 86 has a suitable manually adjustable cam engaging element 90 and cam follower 87 has a similar element 91 both of which cooperate with cam 92 carried by the piston rod 93 of the piston mounted in cylinder 17.

Cradle end elements 42 and 44, carrying their guide bars, separators and spacers, are rotated about rod 41 by rocker shaft 94 which is journaled at one end in bracket 23 and at the other end in bracket 24. Rocker shaft 94 is linked to element 42 through rocker arm 95 which is secured to shaft 94 and link 96 which is pivoted to element 42 at 97 and to arm 95 at 98. Rocker shaft 94 is also linked to element 44 through rocker arm 99 which is secured to shaft 94 and link 100 which is pivoted to element 44 at 101 and to rocker arm 99 at 102. Cradle end elements 43 and 45 carrying their guide bars, separators and spacers are rotated about rod 41 by an identical mechanical arrangement best seen in part in Figs. 3 and 4 where 103 is the rocker shaft, 104 a rocker arm pivoted at 105 to link 106 which is in turn pivoted to element 43 at 107. Rocker shafts 94 and 103 are rotated by L-shaped arms 108 and 109, best seen in Fig. 4, which are secured to shafts 84 and 103, respectively, adjacent each other at the ends of their longer arms. Arm 109 is provided with an L-shaped slot 110 and arm 108 is provided with a corresponding slot 111. Driving rollers 112 are mounted in slots 110 and 111 and are in turn rotatably mounted on shaft 113 carried by slide 114. Slide 114 is mounted for vertical reciprocating movement in tracks 115 secured to bracket 23 and extending downwardly into slot 12 of machine bed 11. Slide 114 is reciprocated by a piston mounted in a cylinder 116 supported in slot 12 of machine bed 11 below and

adjacent bracket 23 (Fig. 1). This piston has a piston rod 117 which is coupled to slide 114 by link 118.

As best seen in Figs. 3, 4 and 7, a plurality of forming plates 119 are slidably mounted in cooperating pairs on rod 41, each pair having a common pivot 120. Rods 121 and 122 guide plates 119 as they slide over rod 41. Rod 121 is carried by and secured to cradle end elements 42 and 44 and rod 122 is carried by and secured to cradle end elements 43 and 45. Consequently, when the cradle end elements are rotated about rod 41 into open and closed positions each pair of plates 119 will be rotated about rod 41 into open and closed positions. Each plate 119 is semi-circularly cut away at 123 to embrace the tube being formed into the corrugated vessel as is well known in this art. Each pair of plates 119 may be kept in alignment by any suitable means here shown as aligning spools 124. Pairs of plates 119 are urged together to the right, as seen in Figs. 1, 2 and 7, along rods 41, 121 and 122 by springs surrounding these rods, spring 125 surrounding rounding rod 41 being seen in Fig. 7 and spring 126 surrounding rod 121 being seen in Fig. 1. It will be understood that the number of pairs of plates 119, their thickness and the size of opening 123 will be determined by the number and size of corrugations and size of tube as is well known in the art.

As seen in Figs. 3 and 4, each right-hand forming plate of each pair of forming plates 119 is provided with a latch 289 pivoted to the plate at 290 and provided with a latch stud receiving opening 291. Each left-hand forming plate of each pair of forming plates 119 is provided with a latch stud 292 to be received in opening 291. Cradle end elements 43 and 45 are provided with similar latches and cradle end elements 42 and 44 are provided with similar latch studs. Longitudinally extending shafts 293 and 294 couple the several latches 289 together so that they will operate as a unit. The latch 289 carried by cradle end element 43 is provided with spaced fingers 295 and 296 designed to receive finger 291 carried by slide 114.

As seen in Fig. 6, a tubular member 127 is slidably mounted on piston rod 93. Piston rod 93 has a collar 128 secured to its outer end. A spring 128' surrounds rod 93 within tubular member 127 and abuts collar 128 and the end of member 127 to urge member 127 to the left as seen in this figure. Member 127 is centrally bored and threaded at 129 to receive closure member 130. Closure member 130 is in turn centrally bored and threaded to receive the threaded shaft 131 of ram 132, lock nuts 133 being provided to lock the ram assembly in position after adjustment. Ram 132, driven by the piston in cylinder 17 at the proper time in the cycle of operation, effects the movement of the pairs of plates 119 toward each other to form the corrugations.

Mounted on the right end of machine bed 11 as seen in Fig. 1a are brackets 133 and 134 supporting between them a cylinder 135 the assembly being locked together by bolts 136. A piston is mounted in cylinder 135 and is provided with a piston rod 137. Fluid under pressure is admitted to one side of cylinder 135 through manually adjustable valve 138 and to the other side through manually adjustable valve 139.

Piston rod 137 carries sealing head unit 140 which is mounted for reciprocation on guide rods 141 and 142 which are secured in parallel relationship at one end to bracket 133 and their

other ends to bracket 24. Sealing head unit 140 is shown in enlarged detail in Fig. 8 and is there seen to comprise a body member 143 bored to receive bearings 144 and 145 which are mounted on rods 142 and 141 respectively. Body 143 is centrally bored at 146 with reduced diameter at 147 to form annular shoulder 148. Mounted for movement in body 143 is member 149 provided with an annular shoulder 150 to engage shoulder 148 to form a stop in one direction of movement. Member 149 is externally threaded at 151 to receive lock ring 152 for nut 153. Member 149 is internally bored at 154 with reduced diameter at 155 to receive arbor base 156. Arbor base 156 is of reduced diameter at 157 to form a shoulder 158. A spring 159 embraces arbor base 156 and engages shoulders 158 and 160 to urge member 149 to the right as seen in this figure. Arbor base 156 is secured to body member 143 as by bolts 161 and is internally bored and threaded at 162 to receive piston rod 137.

Member 149 is internally bored and threaded at 163 to receive sealing collar 164. Arbor base 156 is internally bored and threaded at 165 to receive arbor 166. Slidably mounted on arbor 166 and within sealing collar 164 are metal rings 167 and 168 separated by rubber ring 169. The inside diameters of these rings are slightly greater than the outside diameter of the tube to be corrugated. The diameter of arbor 166 is determined by the diameter of the tube to be formed into the corrugated wall so that the tube will fit loosely on the outer end of arbor 166 and snugly inside the sealing collar. The length of arbor 166 is determined by the finished length of the corrugated wall being formed.

Member 156 is centrally bored at 170 and arbor 166 is centrally bored at 171 in extension thereof so that fluid under corrugating pressure may be supplied to the interior of the tube on the arbor as will more fully appear hereafter.

The operation of the machine is controlled by a foot pedal 172 (Figs. 1, 1a, 2 and 2a). Pedal 172 is mounted for rotation about a horizontal axis in a frame 173 secured at one end to tie rod 174 and supported at its other end by support rod 175 which is secured at its upper end to machine bed 11. Pivotaly engaging pedal 172 is operating link 176 which is pivoted to bell crank 177 at 178. Bell crank 177 is mounted for rotation at 179 on machine bed 11. A spring 180 acting on roller cam follower 180' which engages centering cam surface 177' formed on the right edge of bell crank 177 returns bell crank 177 to its neutral position when foot pedal 172 is returned to its neutral position. Arm 181 is mounted for rotation on bell crank 177 at 182 and terminates in an inwardly turned and hooked extension 183. A lever 184 is rotatably mounted on machine bed 11 at 185 and carries roller 186 to engage arm 181. A spring 187 is secured to lever 184 and to machine bed 11 to urge lever 184 into engagement with fixed stop 184'. Bell crank 177 carries extension 188 to which link 189 is pivoted at 190. Link 189 is slotted at 191 (Fig. 2a) to engage the actuating member of pilot valve 192 to reverse the operation of the machine as will appear more fully hereafter.

A connecting rod 193 is pivoted to arm 181 at 194 and is connected to rocker arm 195 at pivot 196. Rocker arm 195 is mounted for rotation on machine bed 11 at 197 and is slotted at its upper end at 198 to receive the pin of clevis 199 carried by sliding rod 200. Rod 200 is mounted for longitudinal reciprocating movement in bearings 201

secured to machine bed 11 (Fig. 2) and carries a lug 202 to actuate pilot valve 203. Rod 200 also carries a lug 204 which is engaged at the proper time in the cycle of operation of the machine by a dog 205 pivoted at 206 to arm 207 which is secured to shaft 208. Shaft 208 extends across machine bed 11 (Fig. 3) and is journaled for rotation therein. Dog 205 is biased into position to engage lug 204 by spring 209. Arm 207 is urged into clockwise rotation, as seen in Fig. 1, by a spring 210. Shaft 208 carries finger 211 (Fig. 3) which engages the underside of slide 114 so that downward movement of slide 114 will move finger 211 downward, rotating shaft 208 and arm 207 in a counterclockwise direction as seen in Fig. 1. Upward movement of slide 114 permits spring 210 to rotate arm 207 and shaft 208 in a clockwise direction as seen in Fig. 1 and to maintain finger 211 in contact with slide 114. Piston rod 117 carries an extension 212 (Fig. 2) to which a link 214 is pivoted at 213. Link 214 is pivoted at 215 to crank 216. Crank 216 is mounted for rotation at 217 on machine bed 11 and is so designed that its extension 218 will be rotated into engagement with the end of rod 200 when piston rod 117 is in raised position. Extension 212 carries arm 219 extending downwardly outside machine bed 11 to which is secured a cam 220 to operate pilot valve 221 in the appropriate time in the cycle of operation of the machine as will appear more fully hereafter.

Sealing head unit 140 has rod 222 secured thereto for movement therewith (Fig. 1a). Rod 222 terminates in finger 223 which is designed to engage hooked extension 183 of arm 181 when sealing head unit 140 is in its withdrawn position. Rod 222 also carries a cam 224 which engages and operates pilot valve 192 at appropriate times in the cycle of operation of the machine as will more fully appear hereafter.

The hydraulic system next to be described is shown in detail in Figs. 1-2a and in simplified diagrammatic form in Fig. 9. Briefly this system comprises a source of fluid under pressure and a return thereto. Depression of foot pedal 172 to machine-run position shifts a pilot valve which in turn supplies fluid under pressure to open valves to supply fluid under pressure to the spacer reset cylinder and the sealing head unit cylinder, moving the spacer reset head to its outer position where it remains until the last stages of the cycle of operation of the machine. Fluid under pressure is also supplied to a pressure booster cylinder but not admitted at this time to the cylinder. As the spacer reset head moves, the sealing head unit with a tube on its arbor starts toward the open cradle. As the tube enters the cradle the sealing head unit operates a pilot valve which in turn opens another valve to admit fluid under pressure to the sealing head unit and the interior of the tube. As the sealing head unit finishes its stroke the tube is pushed against the ram in the end of the cradle and is seated firmly in the sealing head unit. Fluid pressure builds up in the tube and in the line thereto. This increased pressure operates a pressure responsive valve which opens to admit fluid under pressure to the cradle operating cylinder to raise the piston therein and close and lock the cradle and forming plates about the tube. Upward movement of this piston shifts a pilot valve for the ram cylinder and mechanically locks the first pilot valve

against any movement tending to reverse the machine.

As the cradle closing piston reaches its upward position pressure builds up behind it and this increased pressure is used to open a pressure responsive valve to admit fluid under pressure, previously supplied, to the pressure booster cylinder. The fluid under bulging pressure from this booster cylinder is then admitted to the tube and bulges the tube between the forming plates, as is well known in the art. When a predetermined bulging pressure has been reached in the tube a pressure responsive valve opens to admit fluid under pressure to a pressure responsive valve which in turn opens to admit fluid under pressure to the ram cylinder. The ram commences its stroke by withdrawing the spacers from between the forming plates and continues its stroke while the forming plates move together, collapsing the tube and forming the corrugated wall. When the ram reaches the end of its stroke pressure builds up behind its piston and this increased pressure is used to bleed the high pressure fluid from the formed corrugated wall and the high pressure line. Loss of pressure in the high pressure line allows the pressure responsive valve associated with the cradle closing cylinder to supply fluid to this cylinder to unlock and open the cradle and forming plates. Opening the cradle mechanically reverses the first pilot valve described above and also shifts the pilot valve for the ram cylinder. Reversal of the first pilot valve described above starts the spacer reset piston on its return or spacer reset stroke, starts the sealing head unit piston on its return stroke and starts the booster piston on its return stroke. Shifting of the pilot valve for the ram cylinder returns the ram to its initial position. On its return stroke the sealing head unit, carrying the finished corrugated wall on its arbor to a position outside of the cradle where it may be removed from the arbor by any suitable means, returns the pilot valve controlling the admission of fluid pressure to the tube to its original position. Return of the booster piston draws a fresh charge of fluid into the pressure booster for the next cycle.

A machine setup valve is also provided in this hydraulic system by which the valve admitting fluid to the cradle operating cylinder and piston can be manually controlled to open or close the cradle independently of the cycle of machine operation during adjustment of the forming plates, spacers, etc.

Referring now to Fig. 9 which shows the hydraulic system for the machine, a pipe 225 leads from a source of fluid under pressure to a valve 226. Valve 226 is any suitable four-way, pilot-operated, hydraulic, directional flow control valve with its drain port connected by return pipe 227 to the source of fluid under pressure. Valve 225 is connected by pipe 228 and manually adjustable valve 19 to one side of spacer reset cylinder 16. The other side of spacer reset cylinder 16 is connected through manually adjustable valve 20 and pipe 229 to the upper side of valve 226. A by-pass and check valve 230 is provided around valve 20. Valve 226 is connected through pipe 231 to a valve 232 which is a pressure operated, spring loaded, check valve. The other side of valve 232 is connected by pipe 233 to the lower side of pressure booster cylinder 234. A by-pass and check valve 235 is provided from pipe 233 around valve 232 and back to

pipe 231. A pipe 236 leads from pipe 231 through manually adjustable valve 138 to one side of sealing head unit cylinder 135 and the other side of cylinder 135 is connected through manually adjustable valve 139 by pipe 237 to pipe 229. Pipe 238 connects the upper end of booster cylinder 234 to the upper side of valve 226.

The hydraulic system operating the cradle opening and closing cylinder and piston 116 includes a pipe 239 leading through a manually operable valve 240 to valve 241. Valve 241 is any suitable four-way, pilot-operated, hydraulic, directional flow, control valve with an adjustable spring in place of the pilot pressure cap to return the valve spool upon release of pilot pressure. Valve 241 is connected by pipe 242 to the lower end of cylinder 116 and is connected by pipe 243 to the upper end of cylinder 116. Pipe 244 connects the drain side of valve 241 to pipe 227.

The hydraulic system operating the ram piston and cylinder 17 includes pipe 225 connected by pipe 245 to valve 246 which is any suitable, four-way, pilot-operated, hydraulic, directional flow, control valve. The drain side of valve 246 is connected by pipe 247 to pipe 227. Valve 246 is connected to the left side of cylinder 17 through pipe 248, manually adjustable valve 249 and check valve 250 and is connected to the other side of cylinder 17 through pipe 251. The left side of cylinder 17 is connected to return line 227 by pipe 252, pilot valve 221 and pipe 253.

The pressure booster system is seen in Figs. 1a, 2a and 9 and is described with particular reference to Fig. 9. The piston in cylinder 234 drives a piston of smaller area in cylinder 254. The pressure increase is in proportion to the ratio of these areas. The upper end of cylinder 254 is connected by pipe 255 to pipe 256 which is in turn connected through check valve 257 to a source 258 of fluid under pressure. Pipe 256 also connects into valve 259 which is any suitable four-way, pilot-operated, hydraulic, directional flow, control valve with one port closed. The upper pressure cap of valve 259 is elongated and contains a spring to bias the valve spool against the other pilot pressure cap and into drain position when pilot pressures are equal in both caps.

The drain port of valve 259 is connected by pipe 260 to drain pipe 261. Valve 259 is connected by pipe 262 to valve 263 which is an adjustable, balanced type, pressure control valve of the unloading type used to set and maintain tube bulging pressures. Valve 263 is connected by pipe 264 to manually adjustable valve 265 and through flexible conduit 266 to the central boring 170 of member 156 and boring 171 of arbor 166 (Fig. 8). A pressure gauge 267 may be inserted in pipe 264 if desired. Valve 263 is connected by pipe 268 to valve 269. Valve 269 is any suitable, reverse acting, bellows operated, poppet type, regulator valve connected by pipe 270 to drain pipe 261. Pipes 271 and 272 connect pipe 268 to the bellows of valve 269.

The hydraulic system for operating the several pilot valves above described includes a pipe 273 connecting pipe 225 with machine setup pilot valve 274 and furnishes fluid under pressure to valve 274. Pilot valve 274 furnishes fluid under pressure to the other pilot valves when in normal operating position. The drain port of valve 274 is connected by pipe 275 to pipe 227. Valve 274 supplies fluid under pressure when in normal operating position to pilot valve 203 through pipe 276. Pilot valve 203 is connected by pipe 277 to one pilot pressure cap of valve 226 and is con-

nected to the other pressure cap by pipe 278. Valve 203 supplies pressure to pilot valve 192 through pipe 279. Pilot valve 192 is connected to the elongated pressure cap of valve 259 by pipe 280 and to the other pressure cap by pipe 281. A pipe 282 connects pilot valve 192 and pilot valve 221.

Pipe 264 is connected by pipe 283 to three-way valve 284, which is connected to pilot valve 274, and by pipe 285 to the pressure cap of valve 241. Three-way valve 284 when in normal operating position closes the connection to pilot valve 274 and opens the connection between pipes 283 and 285.

Pipe 271 is connected by pipe 286 to one pressure cap of valve 246. The other pressure cap of valve 246 is connected by pipe 287 to the upper end of cylinder 116. The lower end of cylinder 116 is connected by pipe 288 to the pressure operating mechanism of valve 232.

With the mechanical elements and the hydraulic operating system of this machine set up as above described, when it is desired to manually control the opening and closing of the cradle independently of the cycle of operation of the machine, as when replacing or adjusting forming plates, spacers, spacer separators or for other purposes, three-way valve 284 is rotated to cut off pipe 283 and connect pipe 285 to pilot valve 274. Manual operation of pilot valve 274 then supplies fluid under pressure from pipes 225 and 273 to pipe 285 and the pressure cap of valve 241. Valve 241 then opens to admit fluid under pressure from pipes 225 and 239 to pipe 242, valve 240 being manually adjusted to obtain the desired rate of flow of fluid in pipe 242. Fluid under pressure is supplied from pipe 242 to the lower side of the piston in cylinder 116 raising the piston and piston rod 117. Upward movement of rod 117 through link 118 moves slide 114 and rollers 112 upwardly. Upward movement of rollers 112 rotates arm 108 in a counterclockwise direction and arm 109 in a clockwise direction as seen in Figs. 3 and 4 rotating shaft 94 in a counterclockwise direction and shaft 103 in a clockwise direction. Counterclockwise rotation of shaft 94 rotates rocker arms 95 and 99 in a counterclockwise direction and through links 96 and 100 rotates cradle end elements 42 and 44 about rod 41 in a counterclockwise direction to closed position.

Clockwise rotation of shaft 103 imparts the same rotation to rocker arm 104 and through link 106 to cradle end elements 43 and 45 rotating these end elements into closed position. Slide 114 has only partially completed its upward movement when the cradle end elements reach their closed position. By reason of the shape of slots 110 and 111 in arms 108 and 109 slide 114 is enabled thereafter to continue its upward movement. Rotation of the cradle end elements also rotates the pairs of forming plates 119 since each pair of forming plates 119 is pivoted on rod 41 and supported for movement with the cradle end elements by rods 121 and 122. The spacer assembly also rotates with the cradle end elements and the spacers remain between the pairs of forming plates. As the cradle end elements move into closed position fingers 295 and 296 are moved into the path of upward movement of finger 297 and as slide 114 continues its upward movement after the cradle end elements and pairs of plates 119 have reached closed position finger 297 engages between fingers 295 and 296 and rotates all of the latches 289 into position where they engage latch

stud 292, locking the cradle end elements and pairs of plates 119 together.

When pilot valve 274 is manually shifted to its original position pressure is relieved in the pressure cap of valve 241 and valve 241 under action of its spring opens communication between pipe 225 and the pipe 243 supplying fluid under pressure to the top of cylinder 116 and connecting pipe 242 through pipe 244 to return pipe 227. The piston in cylinder 116 starts downwardly and moves piston rod 117 in the same direction. Slide 114 moves downwardly and during the first part of this movement finger 297 opens latches 289. After latches 289 have opened, further downward movement of slide 114 reverses the rotation of the several elements above described and the cradle end elements open carrying the forming plates and separator assemblies with them, opening the pairs of plates 119.

After suitable adjustment of the cradle assembly has been made and it is desired to operate the machine in its automatic cycle, valve 284 is rotated to its normal position closing its connection to pilot valve 274 and opening communication between pipes 283 and 285. A tube is then placed on arbor 166 and foot pedal 172 depressed to draw link 176 downward rotating bell crank 177 about its pivot 179 in a counterclockwise direction. Counterclockwise rotation of bell crank 177 moves arm 181 to the right since hooked extension 183 is engaged by finger 223. Movement of arm 181 to the right through rod 193 rotates rocker arm 195 in a clockwise direction and pilot valve 203 is moved by rod 200 and cam 202 to machine run position. Counterclockwise rotation of bell crank 177 has no influence on pilot valve 192 because of slot 191 in link 189. With pilot valve 203 in machine run position fluid under pressure is supplied from pipe 225 through pipe 273, pilot valve 274, pipe 276 and pilot valve 203 to pipes 278 and 279. Fluid pressure in pipe 278 operates valve 226 to admit fluid under pressure from pipe 225 into pipes 228 and 236 to start the spacer reset piston and the sealing head unit piston in movement. Pressure is also supplied to pipe 231 but backs up against closed valve 232 and check valve 235. The spacer reset head 31 is moved to its outward position and remains there until later in the cycle.

Movement of the sealing head unit piston moves sealing head unit 140 to the left as seen in Figs. 1 and 1a and finger 223 releases arm 181. Further movement of sealing head unit 140 to the left brings cam 224 into engagement with pilot valve 192, operating this valve to supply fluid under pressure from pipe 279 through pilot valve 192 to pipe 281 and valve 259. Valve 239 is operated to admit fluid under pressure from pipe 258 into pipe 264, flexible pipe 266 and the interior of the tube on arbor 166 just before the tube engages ram 132. Movement of the sealing head unit 140 continues until the end of the tube on arbor 166 comes into engagement with ram 132. The open end of the tube is then pressed into sealing collar 164 and rings 167, 168 and 169 seal the open end of the tube against loss of pressure by squeezing rubber ring 169 inwardly against the tube. Back pressure then builds up in pipes 266 and 264 and passing through pipes 263, valve 284 and pipe 285 operates valve 241. Valve 241 then admits fluid under pressure from line 225 to pipe 262 and the underside of the piston in the cylinder 116 which moves upward closing and locking the cradle and pairs of forming plates 119 about the tube as above described.

When the piston in cylinder 116 reaches the top of its stroke pressure builds up behind it and is taken by pipe 288 to valve 232 and valve 232 is opened admitting fluid under pressure from pipe 225, valve 226 and pipes 231 and 233 to the bottom of booster cylinder 234. The piston in cylinder 234 moves upward and fluid under bulging pressure backs up against check valve 257 and passes through pipes 255 and 256, valve 259, pipe 262, valve 263, pipe 264, valve 265, flexible pipe 266 and borings 170 and 171 to the interior of the tube bulging the same between the forming plates as is well known in the art.

As soon as the bulging pressure for which valve 263 is preset is reached valve 263 unloads and admits fluid under pressure to pipes 271 and 286. Valve 246 is operated by this fluid pressure to admit fluid under pressure from pipe 225 through pipe 248, valve 249 and check valve 250 to the left side of cylinder 17 starting the piston in this cylinder on its ram stroke. Valve 269 is pressure operated to assure the right amount of pressure in pipe 271. It will thus be seen that by reason of this interrelation of pressures the ram stroke cannot start until the proper bulging pressure has been reached and the tube bulged between the forming plates.

Ram 132 does not start its compression stroke until a predetermined movement of piston rod 93 has occurred. This lost motion is provided by piston rod 93 sliding in cylinder 127 until ring 128 engages the end of closure member 130. During this lost motion cam 92 advances and forces cam followers 86 and 87 outwardly (Fig. 6) rotating arms 80 and 82 outwardly which in turn rotates shafts 84 and 85 and arms 81 and 83 outwardly. Outward rotation of arms 80, 81, 82 and 83 carries bars 74 and 75 with them and these bars engaging in slots 62 of spacers 58 move spacers 58 from between the pairs of forming plates 119. Thereafter piston rod 93 picks up ram 132 and moves ram 132 on its compressing stroke as the pairs of die plates move together and completing the corrugations.

When the piston in cylinder 17 reaches the end of its ram stroke pressure builds up behind it and is taken through pipe 252 to pilot valve 221. Valve 221 has meanwhile been actuated on the upward stroke of piston rod 117 by cam 220 to admit this fluid pressure to pipe 292, pilot valve 192 and pipe 280 to valve 259 where it balances valve 259 and allows the valve spring to move the valve poppet of valve 259 to drain position and the high pressure system is drained through pipes 260 and 261.

Release of pressure in the high pressure system releases pressure in pipes 283 and 285 and valve 241 is returned by its spring to admit fluid under pressure from pipe 225 to pipe 243 and the top of cylinder 116. The piston in cylinder 116 then starts down and fluid beneath it drains through pipe 242, valve 241 and pipe 244 to pipe 227. Downward movement of this piston and its rod 117 unlocks the cradle end elements and forming plates as above described and rotates them to open position.

Downward movement of slide 114 rotates finger 211 and shaft 288, rotating arm 207 counterclockwise as seen in Fig. 1, and dog 205, which snapped under lug 204 on the upward movement of slide 114, engages lug 204 and slides rod 200 to the left reversing pilot valve 293.

As the piston in cylinder 116 finishes its downward movement pressure builds up behind it and is taken by pipe 287 to one pressure cap of valve 246 operating valve 246, since pressure in pipe 286

(Fig. 9) has now been released, to admit fluid under pressure from pipe 225 to pipe 251. The piston in cylinder 17 cannot start its return stroke however until the downward movement of piston rod 117 and cam 220 operates pilot valve 221 to drain cylinder 17 through pipe 252, pilot valve 221, pipe 253 and pipe 227. Drainage cannot take place through pipe 248 because of check valve 250. A safety feature is thus provided preventing the ram 132 from returning to its starting position until the cradle is completely open and the pairs of forming plates 119 removed from the now corrugated wall. As piston rod 93 nears the end of its return stroke cam 92 clears cam engaging elements 90 and 91 and these drop in behind cam 92 in readiness for the next cycle of the machine. Final movement of piston rod 93 in this direction compresses spring 128 in the lost motion device in tubular member 127 since motion of member 127 is stopped by bracket 23 and sets the lost motion device for the next machine cycle.

The reversal of pilot valve 203 described above admits fluid under pressure from pipe 225, pilot valve 274 and pipe 276 to pipe 277 actuating valve 226 to admit fluid under pressure from pipe 225 to pipes 229 and 233. Fluid under pressure in pipe 229 passes through pipe 237 and valve 139 to cylinder 135 starting the sealing head unit piston on its return stroke, the fluid behind this piston draining through valve 138, pipe 236 and valve 226 to pipe 227, valve 232 having meanwhile been closed by its spring when cylinder 116 draining through pipe 242 drained pipe 288. Return of sealing head unit 140 to its starting position through the action of cam 224 returns pilot valve 192 to its starting position and finger 223 engages hooked extension 183 of arm 181.

Arbor 166 of sealing head unit 140 carries the finished corrugated wall with it clear of the cradle and at this time the corrugated wall may be removed from arbor 166 by any suitable means, manual or mechanical, and another tube placed on arbor 166 for the next cycle of the machine.

Fluid under pressure in pipe 229 backs up against check valve 238 and passing through valve 20 starts the piston in the spacer reset cylinder 16 on its movement to the left which is the work stroke for this piston. Fluid drains from cylinder 16 on this stroke through pipe 228 and valve 226 to pipe 227. As best seen in Figs. 4 and 7, at the time of this work stroke the cradle is open and the spacers 58 in their withdrawn position are in the path of movement of rollers 39 and 40. As spacer reset head 31 moves to the left drawn by piston rod 32 and the piston in cylinder 16, rollers 39 and 40 are rolled over and engage cam surfaces 64 of spacers 58 moving spacers 58 inwardly. The offset centers of rollers 39 and 40 permit this movement to take place without shock and over a longer period of time. Inward movement of spacers 58 move cam surfaces 63 thereof between the pairs of forming plates 119 separating the pairs of forming plates 119 against the compression of springs 125 and 126. Inward movement of spacers 58 is continued until the bodies of spacers 58 are between the pairs of forming plates 119 and the pairs of forming plates 119 are in proper spaced relationship for the next machine cycle. Movement of spacers 58 inwardly carries bars 74 and 75 inwardly and rotates arms 80, 81, 82 and 83 inwardly.

Fluid under pressure in pipe 238 starts the booster piston in cylinder 234 on its return stroke, the fluid in this cylinder exhausting through pipe 233 and check valve 235 to pipe 231 and valve 229

to pipe 221. Downward movement of the piston in cylinder 234 moves the piston in cylinder 254 downward drawing a fresh charge of fluid into cylinder 254 through check valve 257 and pipe 258 for the next cycle of the machine.

The machine is now ready for the next cycle of operation and if foot pedal 172 is kept by the operator in depressed position it will start its next cycle automatically and without pause. If foot pedal 172 has been released the machine will stop until the pedal is again depressed to depress link 176 to shift pilot valve 203 to machine run position.

Reversal of the machine may be initiated at any time in its cycle of operation and thereafter the several elements of the machine will return to their initial positions in their proper sequence. The machine is reversed by movement of foot pedal 172 to raise link 176 to rotate bell crank 177 in a clockwise direction as seen in Fig. 1a. If the sealing head unit 140 has not yet shifted pilot valve 192 so that the cradle has closed and rotated bell crank 216 into engagement with the end of sliding rod 200, the reversal of the machine is performed by the direct reversal of pilot valve 203. Under these circumstances clockwise rotation of bell crank 177 rotates pivot 182 in the same direction and the same movement is imparted to arm 181 which is rotated about cam roller 186 on cam arm 184. Link 193 is thus moved to the left, rotating rocker arm 195 in a counterclockwise direction which in turn slides rod 200 to the left reversing pilot valve 203 by action of lug 202. The machine then reverses and the several elements return to their initial positions in proper sequence as above described.

If the sealing head unit 140 has shifted pilot valve 192 so that the cradle is closed and the operator actuates foot pedal 172 to reverse the machine, pilot valve 203 cannot be reversed since bell crank 216 has been rotated into engagement with the end of sliding rod 200 locking pilot valve 203 in machine run position. Link 193 is also held against movement and clockwise rotation of bell crank 177 rotates arm 181 about pivot 194 moving cam roller 186 and cam arm 184 in clockwise rotation. Clockwise rotation of bell crank 177 draws link 189 to the right and as the actuating element of pilot valve 192 has been shifted by sealing head unit 140 to the left end of slot 191 (Fig. 2a) link 189 reverses pilot valve 192. Reversal of pilot valve 192 supplies fluid under pressure to pipe 280 shifting valve 259 to drain position, draining the high pressure system of the machine and effecting reversal of the several elements and their return in sequence to their initial positions as above described. It will now be apparent that no matter at what point in its cycle of operation the machine is reversed the several elements thereof will be returned to their initial position in proper sequence without damage to the machine.

A modified piping layout is partially and schematically shown in Fig. 12. This system dispenses with certain of the parts in the system above described, notably pilot valve 221 and three-way valve 284, and utilizes any suitable four-way, pilot operated, hydraulic, directional flow, control valve with two ports blocked in place of pressure operated, spring loaded check valve 232. The cycle of operation of the machine is, however, exactly the same. In this system when the machine cycle is started by

actuating pilot valve 203 fluid under pressure is admitted to pipe 278 which actuates valve 226 to admit fluid under pressure to pipes 228, 236 and 231 as before. Fluid under pressure is also admitted to pipes 291 and 292 to assure that valves 246 and 232 remain closed. When pressure builds up in pipe 264 it is taken by pipe 285 in this system through pilot valve 274 and pipe 293 to one pressure cap of valve 241 to actuate valve 241 to close the cradle. Pressure built up when the cradle is closed passes through pipe 288 to one pressure cap of valve 232 to open valve 232 and admit fluid under pressure from pipe 231 to pipe 233 and cylinder 234. When bulging pressures are reached valve 263 unloads as before and valve 246 is actuated to drive the ram. Pressure built up when the ram reaches the end of its stroke is taken by pipe 252 to one pressure cap of valve 259 to bleed the high pressure system and to supply fluid under pressure to pipe 290 which is connected to one pressure cap of valve 241 to actuate valve 241 to supply fluid under pressure to open the cradle and return the ram to its initial position. Opening of the cradle shifts pilot valve 203 as before and the reversal of the machine proceeds as above described.

As will be apparent, adjustment of the hand-operated valves heretofore referred to enables the rate of flow theretofore and the development of pressure theretofore to be nicely predetermined so that the desired intervals of time will transpire between the successive operations in the sequence described, and where pressure responsive valves are used proper selection of the actuating pressure as well understood in the art will effect a like result.

It will now be apparent that the present invention provides a novel hydraulic press for forming expansible and contractible corrugated metallic walls in which the several steps are performed automatically at the proper time. When the tube is in place in the cradle and between the open forming plates means are automatically actuated to close the open end of the tube, after which controlled hydraulic pressure, thereafter bulging and hydraulic pressure supplied by novel pressure booster means is admitted automatically to the interior of the tube to form bulges in the tube between the pairs of forming plates. The spacers between the pairs of forming plates are then automatically removed and thereafter novel means are automatically actuated so that the pairs of forming plates approach each other to complete the formation of the expansible and contractible corrugated wall. Novel automatic means are then provided to drain the liquid under pressure from the system leading to the finished wall as soon as it is formed, and thereafter to unlock and open the cradle and withdraw the corrugated wall from the forming plates. Novel means are provided for automatically interposing the spacers between the several pairs of forming plates before the start of the next forming cycle, it also being apparent that the present invention provides novel means for locking the forming plates of each pair together and novel means for rotating the forming plates into and out of closed position to allow their ready removal and adjustment.

To those skilled in the art changes in or modifications of the above described illustrative embodiment of the present invention will now be suggested without departing from the inventive concept of the present invention. For instance

if metallic tubes having both ends open are to be formed into the expansible and contractible corrugated metallic wall, then instead of using ram 132, as described, a second end sealing assembly would be used and properly timed in the cycle to close the end of the tube before hydraulic pressure is admitted at the other end of the tube, or both end sealing devices could be timed to operate together and to both admit hydraulic pressure to the tube at the same time. In such a situation as this the second end sealing assembly, with proper pressure booster means, as described, would be mounted on piston rod 93 in place of ram 132 and would have the dual function of both end sealing the tube and compressing the bulged tube to form the expansible and contractible metallic wall. Further and other changes in the hydraulic system, in the spacer assembly, in the various locking devices, etc. will now be suggested to those skilled in the art, and therefore to determine the scope of the present invention reference should be had to the appended claims.

What is claimed is:

1. In an apparatus of the character described, in combination with pairs of cooperating forming plates, pairs of frame elements mounted for rotational movement into open and closed positions in which corresponding plates of said pairs are slidably mounted for relative rotational movement, a source of fluid pressure, means for rotating said frame elements and plates into closed position and for locking said frame elements and the plates of said pairs together, movable means for automatically closing the open end of a tube in position in said plates before said plates are in closed position, a valve responsive to movement of said last named means for admitting fluid under pressure to the interior of the tube when said last named means is in tube closing position, and a pressure responsive valve responsive to the pressure in the tube for energizing said rotating means to rotate said frame elements and plates into closed position about the tube.

2. In an apparatus of the character described, in combination with pairs of cooperating forming plates, a frame in which corresponding plates of said pairs are rotatably and slidably mounted, a source of fluid pressure, fluid pressure means for rotating and for locking the plates of said pairs together, means for sealing the open end of a tube in position in said plates, said sealing means providing a conduit communicating with the interior of said tube, means for moving said sealing means and the tube into sealing relation before said plates are in locked position, a valve for admitting fluid under pressure to said conduit, means responsive movement of said last named means for actuating said valve, a pressure responsive valve responsive to the pressure in said conduit to energize said rotating and locking means, means arranged to be connected with said source of fluid pressure for increasing the pressure thereof to a bulging pressure, fluid pressure means actuated by the fluid pressure in said rotating and locking means to connect said source of fluid pressure with said means for providing a bulging pressure, and means for connecting said means for developing bulging pressure through said tube end sealing means to the interior of the tube only after the plates are in closed and locked position.

3. In an apparatus of the character described, in combination with pairs of cooperating form-

ing plates, a frame in which corresponding plates of said pairs are rotatably and slidably mounted, a source of fluid pressure, fluid pressure means for rotating and for locking the plates of said pairs together, means for sealing the open end of a tube supported in position in said plates, means for moving said sealing means and the tube into sealing relation before said plates are in locked position, a valve for admitting fluid under pressure to the interior of the tube, means responsive to movement of said last named means for actuating said valve, a pressure responsive valve responsive to pressure in the tube for energizing said rotating and locking means, a pressure booster adapted to be connected to the interior of the tube through said sealing means, a pressure control valve between said pressure booster and said sealing means, and fluid pressure means actuated by the fluid pressure in said rotating and locking means for automatically connecting said source of fluid pressure to said pressure booster after said plates are locked together, said pressure booster communicating with the interior of the tube through said sealing means and said pressure control valve operating to maintain a substantially uniform pressure in the tube while bulges are being formed in the tube between said plates.

4. In an apparatus of the character described, in combination with pairs of cooperating forming plates, a frame in which corresponding plates of said pairs are rotatably and slidably mounted, a source of fluid pressure, fluid pressure means for rotating and for locking the plates of said pairs together, spacers adapted to be inserted between the respective pairs of plates, means for supporting a tube and for sealing the open end of the tube in position in said plates before said plates are locked together, cam means for withdrawing said spacers, a ram for actuating said cam means and for collapsing said tube axially, a cylinder and piston for operating said ram, means actuated by the fluid pressure in said rotating and locking means as said plates are locked together for connecting said source of fluid pressure with the interior of said tube to bulge said tube between said plates and means connecting said source of fluid pressure with said cylinder to actuate said ram and said cam means to withdraw said spacers only after bulge forming pressure has been established in said tube and thereafter to move said ram to collapse said tube axially.

5. In an apparatus of the character described, in combination with pairs of cooperating forming plates, a frame in which corresponding plates of said pairs are rotatably and slidably mounted, a source of fluid pressure, fluid pressure means for rotating and for locking the plates of said pairs together, spacers adapted to be inserted between the respective pairs of plates, means for supporting a tube and for sealing the open end of the tube in position in said plates before said plates are locked together, means for withdrawing said spacers, a ram for collapsing said tube axially, a cylinder and piston for operating said spacer withdrawing means and said ram, means actuated by the fluid pressure in said rotating and locking means as said plates are locked together for connecting said source of fluid pressure with the interior of the tube to bulge the tube between said plates, means connecting said source of fluid pressure with said cylinder to withdraw said spacers only after bulge forming pressure has been established in the tube and to there-

after move said ram and collapse said tube axially, and means actuated by the axial movement of said piston to a predetermined position to unlock and open said plates.

6. In an apparatus of the character described, in combination with pairs of cooperating forming plates, a frame in which corresponding plates of said pairs are rotatably and slidably mounted, a source of fluid pressure, fluid pressure means for rotating and for locking the plates of said pairs together, means for supporting and sealing the open end of a tube in position in said plates before said plates are in locked position, means for admitting fluid under pressure to the interior of the tube, fluid pressure means for operating said supporting and sealing means to move the tube into said plates and into sealing position, means responsive to fluid pressure in the tube for connecting said source with said rotating and locking means, and manual means for initiating the operation of said fluid pressure means.

7. In an apparatus of the character described, in combination with pairs of cooperating forming plates, a frame in which corresponding plates of said pairs are rotatably and slidably mounted, a source of fluid pressure, means for rotating and for locking the plates of said pairs together, fluid pressure means for supporting and for sealing the open end of a tube in position in said plates before said plates are locked together, means for admitting fluid under pressure to the interior of the tube, fluid pressure means automatically actuated when said sealing means are in sealing position to actuate said rotating and locking means to rotate and lock said plates about the tube, said last named fluid pressure means being responsive to fluid pressure in the tube, fluid pressure means automatically actuated only after bulges have been formed in said tube for collapsing said tube axially to form corrugations in the bulged tube, and fluid pressure means automatically actuated when said plates have reached a predetermined position to unlock and open said plates.

8. In an apparatus of the character described, in combination with pairs of cooperating forming plates, a frame in which corresponding plates of said pairs are rotatably and slidably mounted, a source of fluid pressure, means for rotating and for locking the plates of said pairs together, fluid pressure means for supporting and for sealing the open end of a tube in position in said plates before said plates are locked together, means for admitting fluid under pressure to the interior of the tube, means responsive to fluid pressure in the tube for connecting said source with said rotating and locking means, and means connected to said source of fluid pressure for increasing said pressure to a bulge forming pressure and then introducing said bulge forming pressure into the interior of said tube only when said plates are locked about said tube, said last named means including a cylinder and a piston, a second piston of smaller area than said first named piston and actuated thereby, a cylinder for said second named piston adapted to be placed in communication with said tube, means actuated by said rotating and locking means as said plates are rotated into locked position to connect said source of fluid pressure with said first named cylinder and pressure responsive means for communicating bulge forming pressure from said second named cylinder to the interior of said tube.

9. In apparatus of the character described in

combination with pairs of cooperating forming plates, frame slidably supporting one plate of each pair of plates, a second frame pivoted to said first frame slidably supporting the other plate of each pair of plates, means for rotating said frames about said pivot to open and close said forming plates, spacers carried by said frames between said pairs of forming plates, means for sliding said spacers in said frames out of engagement with said pairs of plates and means for returning said spacers between said pairs of plates only when said pairs of plates are in open position.

10. In apparatus of the character described in combination with pairs of cooperating forming plates, a frame slidably supporting one plate of each pair of plates, a second frame slidably supporting the other plate of each pair of plates, a common pivot for said frames and said pairs of plates, resilient means urging said pairs of plates together, spacers carried by said frames between said forming plates, spacer separators separating said spacers, means resiliently locking said spacers and said spacer separators in said frames, means for moving said spacers out of engagement with said pairs of plates, means for rotating said frames about said pivot to open and close said pairs of plates, and means for returning said spacers between said plates when said plates are in open position.

11. In apparatus of the character described in combination with pairs of cooperating forming plates, a frame slidably supporting one plate of each pair of plates, a second frame slidably supporting the other plate of each pair of plates, a common pivot for said frames and said pairs of plates, means for rotating said frames about said pivot to open and close said plates, spacers carried by said frames between said pairs of plates, means for moving said spacers out of engagement with said pairs of plates and means for returning said spacers between said pairs of plates including spacer engaging elements mounted for movement parallel to said pivot and so constructed and arranged as to engage said spacers only when said frames and said pairs of plates are in open position.

12. In apparatus of the character described in combination with pairs of cooperating forming plates, a frame slidably supporting one plate of each pair of plates, spacers carried by said frame between said plates, separators carried by said frame between said spacers, resilient means locking said spacers and said separators together in said frame, a second frame slidably supporting the other plate of each pair of plates, spacers carried by said second frame between said plates, separators carried by said second frame between said spacers, resilient means locking said spacers and said separators together in said second frame, a common pivot for said frames and said pairs of plates, means locking each pair of plates together and locking said frames together, means for rotating said frames about said pivot to open and close said pairs of plates and to actuate said locking means when said plates are closed, means for removing said spacers from between said plates, and means for returning said spacers between said pairs of plates only when said frames and said plates are in open position including spacer engaging elements mounted for movement parallel to said pivot.

13. In apparatus of the character described in combination with pairs of cooperating forming plates, spacers between said plates, a source of fluid pressure, fluid pressure means for opening

and closing said plates, fluid pressure means for supporting and end sealing a tube and moving said tube between said plates, means for increasing said fluid pressure to tube bulging pressures and admitting the increased pressure to said tube, means for removing said spacers, means for collapsing said tube, pressure operated spacer reset means, and manually operable pressure means for energizing said tube supporting and moving means to move said tube into said plates, pressure operated means energized by the end sealing of the tube for energizing said plate opening and closing means to close said pairs of plates about said tube, pressure operated means energized by said plate opening and closing means as said pairs of plates are closed for energizing said pressure increasing means whereby said tube is bulged between said pairs of plates, pressure operated means energized by the increased pressure in the tube to first energize said spacer removing means to remove said spacers from between said pairs of plates and to thereafter energize said tube collapsing means, pressure operated means energized after a predetermined movement of said tube collapsing means to energize said plate opening and closing means to open said pairs of plates, and pressure operated means actuated by the opening of said pairs of plates to energize said tube supporting means to move the now formed corrugated tube out of the open pairs of forming plates, to energize said tube collapsing means to return said tube collapsing means to its initial position and to energize said spacer reset

means to reset said spacers between said pairs of plates.

14. In an apparatus of the character described including a tube supporting means, pairs of forming plates, a cylinder and piston for opening and closing said pairs of plates, a ram for collapsing the tube, a cylinder and piston to operate the ram, a source of fluid under pressure, means for admitting fluid under pressure to the tube including a pressure control valve, and a pilot valve actuated by the plate opening and closing cylinder and piston on its closing stroke to admit pressure built up in the ram cylinder at the end of the ram stroke to said pressure control valve to bleed pressure from the now formed tube and actuated by the plate opening and closing cylinder and piston on its opening stroke to permit return of the ram to its initial position.
